RECLINING CHAIR

Leslie R. Maurer, East Palestine, Ohio, assignor to Kenmar Manufacturing Company, East Palestine, Ohio, a corporation of Ohio

Filed Sept. 21, 1959, Ser. No. 57,616

Term of patent 3½ years

(Cl. D15—11)

Figure 1 is a perspective view of the reclining chair showing the front and one side of my new design; and Figure 2 is a perspective view showing the back and the other side thereof.

I claim:

The ornamental design for a reclining chair, as shown.
